William J. Katt, St. Louis, Mo.

Application October 28, 1953, Serial No. 27,360

Term of patent 14 years

(Cl. D62—4)

Fig. 1.

Fig. 3.

Fig. 2.

Figure 1 is a top plan view of a water cooling unit embodying my new design.

Figure 2 is an elevational view thereof.

Figure 3 is a bottom view thereof.

As the water cooling unit is circular and of symmetrical design, the undisclosed portions not shown would appear as shown in Figure 2.

I claim:

The ornamental design for a water cooling unit substantially as shown and described.
